UNITED STATES PATENT OFFICE.

FREDERICK R. BUSSLER, OF QUINCY, MASSACHUSETTS.

DISPENSER FOR LIQUIDS AND OTHER MATERIALS.

1,079,106.

Specification of Letters Patent.

Patented Nov. 18, 1913.

Application filed April 18, 1911. Serial No. 621,765.

To all whom it may concern:

Be it known that I, FREDERICK R. BUSSLER, a citizen of the United States, and a resident of Quincy, in the county of Norfolk and State of Massachusetts, have invented an Improvement in Dispensers for Liquids and other Materials, of which the following description, in connection with the accompanying drawings, is a specification, like characters on the drawings representing like parts.

This invention is an improvement in dispensers for liquid soap or other materials.

The character of the invention may be best understood by reference to the following description of an embodiment thereof appearing in the accompanying drawing, wherein is shown in vertical section an illustrative dispenser embodying the invention.

Referring to the drawing, the illustrative dispenser there shown comprises a reservoir 1 of glass or other material provided at its upper end with an inlet opening 3 to permit filling of the reservoir, said opening being normally closed by a cap 5 removably maintained on said opening by resilient fingers 7 depending from said cap and engaging the wall of said opening.

In dispensers of the class described it is desirable to provide a device which will deliver a small quantity or charge of the soap at a time in order to prevent waste. To this end herein the lower end of the reservoir is provided with a neck 9 containing a lining or bushing 11 of nickel-plated brass or other material, said bushing having a flange 13 for engagement with the outer end of the glass neck of said reservoir and a threaded portion at its inner end to receive a suitable nut 15 thereby preventing said bushing from sliding out of said neck. Suitable gaskets 17 may be interposed between said flange and nut and the portions of the neck adjacent thereto. The outer or flanged

end of said bushing is threaded to receive the upper end of an air-tight delivery cup or chamber 19 provided with a suitable outlet herein in the form of an opening 21 in the bottom of said cup. To control the discharge of the liquid from said reservoir a plunger 23 is provided having its upper end formed to have a sliding fit in said neck bushing and its lower end reduced and extended through said cup outlet 21 to pro-

vide a handle 25 accessible exteriorly of said cup for operating said plunger, as more fully hereinafter described. This handle is of a diameter substantially smaller than that of the outlet to permit the discharge of the liquid through said outlet around said handle. Adjacent said outlet is a flange 27 projecting slightly upward in said cup and constituting a valve seat for coöperation with a valve, herein formed by a flange or shoulder 29 at the juncture of the plunger with its handle and normally closing said outlet. To effect a non-leaking closure of the valve when on its seat a washer 31 of rubber or other suitable material is provided therefor. The plunger 23 is normally thrust downwardly to maintain said valve on its seat by a helical spring 33 encircling said plunger and having one end engaging said plunger flange and its opposite end engaging the outer end of said neck bushing. The upward movement of the plunger is limited by the crowding together of the coils of the spring which encircle the plunger. When the plunger is held on its seat its upper end will be within the neck bushing and thus liquid will be prevented from flowing from said reservoir into the chamber surrounding said plunger, and also liquid in said chamber will be prevented from escape through the outlet thereof. To convey a predetermined quantity or charge of liquid from the reservoir to said chamber said plunger is provided with a lateral recess, pocket or other passage 35 located a short distance from the upper end of the plunger to leave an extent of the latter sufficient for effectively closing the entrance from said reservoir to said chamber. To support the reservoir at its place of use a bracket 37 may be provided having an attaching plate 39 at one end and a ring 41 at its outer end threaded to receive the neck of the reservoir 1.

In operation the outwardly projecting plunger handle is pushed upwardly by the palm of the hand causing the plunger passage to advance upwardly to its dotted position and communicate with the interior of the reservoir. On the occurrence of this event liquid will flow into said passage and on the release of the handle the plunger under the action of its spring will be thrust downward and a charge of liquid will be

conveyed thereby bodily from the reservoir into the chamber. The plunger is then again pushed upwardly as before and a second charge flows into the plunger passage. On the release of the plunger its spring again forces it downward and the liquid charge previously conducted into the air-tight chamber is forced or crowded by the incoming charge out of the chamber past 5 said valve seat, and expelled through the chamber outlet, around the handle and down along the latter into the palm of the hand. The handle in projecting through the outlet assists in conducting and guiding the liquid directly into the palm of the hand. Thus the repeated operation of the handle and its plunger as described takes charges 10 from the reservoir and carries them bodily successively into the delivery chamber. After the first charge has been delivered it will 15 not be necessary in obtaining the next charge to push the plunger upward twice, since a charge will always be in the chamber in readiness to be delivered therefrom 20 on the first upward push of the plunger. Heretofore, in liquid soap dispensers, considerable difficulty has been experienced from 25 the drying and clogging of the delivery mechanism, owing, among other reasons, to the fact that such mechanisms have been exposed to the air between operations. By my 30 invention the discharging mechanism is not exposed to the air at any time excepting on the delivery of liquid therethrough since the mechanism is inclosed in the air-tight 35 chamber and the ingress of air thereto is effectively prevented by the sealing of the outlet end of the chamber by the plunger valve on the valve seat. As shown herein the 40 liquid charge conveyed by the plunger passage 35 is not sufficient to completely fill the chamber surrounding the plunger, but there is a volume of air pocketed above the charge resting on the bottom of the chamber above 45 its outlet. This constitutes a fluid seal beneath the upper valve portion of the plunger which closes the entrance between the reservoir and chamber and effectively prevents any leakage of liquid from said reservoir 50 past said plunger into said chamber. As a result the same volume of liquid charge is always delivered from the chamber. While herein both liquid and air are in the chamber it will be apparent that the seal would exist if 55 either air or liquid were in the chamber. Any tendency to dry or clog the delivery mechanism is further prevented by the fact that said mechanism is continuously surrounded and kept wet by the liquid in the 60 chamber. If there should be at any time an accumulation of dry soap exterior of the valve seat in the annular discharge opening surrounding the handle it is automatically dislodged when the handle is moved upwardly for effecting a discharge operation. 65

A dispenser such as described above provides a very advantageous construction; it is simple in construction and operation, cheap to manufacture and is not liable to get out of order.

While the dispenser has been described herein as applicable for receiving liquid soap, it will be readily understood that it may be used for delivering perfumery or other liquids or materials.

Having described one embodiment of the invention without limiting the same thereto, what I claim as new and desire to secure by Letters Patent is:

1. A dispenser for liquids comprising, in combination, a reservoir; a normally closed substantially air-tight delivery chamber for said reservoir having an outlet; valve means for said outlet; and means for opening said valve means and for taking charges from said reservoir and carrying the same bodily successively into said chamber.

2. A dispenser for liquids comprising, in combination, a reservoir; a normally closed substantially air-tight delivery chamber for said reservoir having an outlet; valve means for said outlet; and a plunger having charge receiving means for carrying charges from said reservoir bodily into said chamber, said plunger having provision for opening said valve means.

3. A dispenser for liquids comprising, in combination, a reservoir; a normally closed substantially air-tight delivery chamber for said reservoir having an outlet; a plunger having a pocket for taking charges from said reservoir and carrying the same bodily successively into said chamber; a handle projecting through said outlet for moving said plunger in one direction; spring means for moving said plunger in an opposite direction; and valve means for said outlet controlled by said plunger.

4. A dispenser for liquids comprising, in combination, a reservoir; a delivery chamber for the latter having a normally closed discharge outlet; valve means for said outlet; a plunger for operating said valve means and having charge receiving means normally communicating with said chamber; a handle projecting through said outlet for moving said plunger to carry said charge receiving means into communication with said reservoir; and spring means for moving said plunger to carry its charge bodily from said reservoir to said chamber, the latter forming an air-tight closure for preventing the drying and accumulation of the liquid on the plunger charge receiving means.

5. A dispenser for liquids comprising, in combination, a reservoir; a delivery chamber for the latter having a normally closed discharge outlet; valve means for said outlet, and means for controlling said valve means and for taking a charge from said

reservoir and carrying the same bodily to said chamber including a plunger having a charge receiving pocket normally communicating with said chamber, the latter forming 5 an air-tight closure for preventing the drying and accumulation of liquid on said plunger pocket.

In testimony whereof, I have signed my name to this specification, in the presence of two subscribing witnesses.

FREDERICK R. BUSSLER.
